UNITED STATES PATENT OFFICE.

ART J. SHIRK AND SOLOMON COHEN, OF NEW YORK, N. Y., ASSIGNEES TO ABRAHAM S. ISERSON, OF NEW YORK, N. Y.

ELECTRIC PRESS IRON.

1,421,588.

Specification of Letters Patent. Patented July 4, 1922.

Application filed April 1, 1920. Serial No. 370,496.

To all whom it may concern:

Be it known that ART J. SHIRK and SOLOMON COHEN, citizens of the United States, and residents of the city of New York, in the 5 county of New York and State of New York, have invented certain new and useful Improvements in Electric Press Irons, of which the following is a specification.

This invention relates to electric press 10 irons and heating means therefor. One of the objects of this invention is to provide a device of the above type characterized by simplicity of construction and efficiency of action in a high degree.

15 Another object is to provide a practical device of the above type in which the parts are unaffected by long-continued practical use. Another object is to provide a device of the above type in which the chance of accidental grounding or short-circuiting is reduced to a minimum. Other objects will be 20 in part obvious and in part pointed out hereinafter.

Certain features herein shown and 25 described are shown, described and claimed in our co-pending application Serial No. 345, 328 filed in the United States Patent Office December 16, 1919, and accordingly are not claimed herein.

30 With the above exception, the invention accordingly consists in the features of construction, combinations of elements and arrangement of parts which will be exemplified in the apparatus hereinafter described 35 and the scope of the application of which will be indicated in the following claims.

In the accompanying drawings, in which is shown one of various possible illustrative embodiments of this invention,

40 Fig. 1 is an elevational view of a stand and switch mechanism embodying our invention with an iron in position on the stand and showing the parts of quick-make and quick-break device in "on" position and 45 showing further the plug means on the iron in the shielded socket members on the stand;

Fig. 2 is a detailed cross-sectional view 50 cut along line 2—2 of Fig. 1 showing the means for shielding the socket terminals on the stand and the means for operating the switch mechanism through insertion of the plug terminals on the iron into the socket terminals; and

Fig. 3 is a detailed cross-sectional view in

plan cut along line 3—3 of Fig. 1 and showing the simplified construction of the quick-make and quick-break switch mechanism; and

Fig. 4 is a cross-sectional view of the switch mechanism with the parts of the quick-make and quick-break device in "off" position.

Referring in detail to the drawing the stand is seen to comprise a base 10 preferably of metal and a support 11 for the electric iron 12 or the like apparatus mounted on pillars 13 upstanding from said base. Extending from the base and secured thereto by means such as screws, clips or rivets 14 is a bottom or support 15 preferably of metal 65 for the casing 15^a removably secured to said bottom and in which are mounted the quick-break switch mechanism and the shielded terminals which will now be described.

Secured within the casing adjacent the top 75 thereof and insulated therefrom as by the block of insulation 16 are the switch clips 17, 17' adapted to be connected to the electric supply as by means of the lead wires 18 which pass into the casing through a threaded bushing 19 suitably insulated from the casing as by the insulating lining 20. The switch clips may be secured in any suitable manner. Thus they may be provided with attaching flanges 21 through which pass the 85 screws 22. Pivoted in operative relation to said switch clips in the manner hereinafter described is a pair of switch blades 30, 30'. These switch blades are jointed at their rear 90 end by a cross piece 31 of insulating material.

The actuating means for the switch mechanism and the means for connecting the electric supply to the iron will now be described and in connection with the description the 95 "fool proof" character of the construction in connection with preventing short circuits through tampering will be brought out.

The casing is formed with a vertical hood 23 in which is embedded a block of insulating material 24 having formed therein a pair of spaced vertical recesses 25, 25'. Within each of these recesses is a metallic socket member 26, 26' each formed preferably from two pieces of sheet metal 26^a and 26^b lining 100 the walls of said recesses. One of said pieces such as 26^a is formed with a flange 26^c whereby it is secured within the casing

to an insulating block 27 disposed immediately beneath the block of insulation 16. The other piece such as 26^b extends further into the casing and is formed at the lower 5 end thereof with an upturned portion 28 between the walls of which are pivoted as by means of the pins 29, 29' of conducting material the switch blades 30, 30'. The sockets 26, 26' are thus in electrical contact 10 with the switch blades and serve both to guide the contacts on the iron and also to connect the electric supply thereto as hereinafter described. A vertical push rod 35, 35' operates in the shielded sockets 26, 26' 15 and has its lower end formed with a projection or ear 36, 36' whereby it is pivoted as by pins 37, 37' to the ends of an equalizer block 32. Except for its connection to the push rods 35, 35', this block 32 is otherwise 20 loose and has an opening 32' therein whereby the bolt 33 carrying the push spring 34 which is of diameter smaller than said opening may pass therethrough so that when either one of the vertical push rods 35, 35' 25 is pushed down, the block is tilted about the bolt as will be readily understood. To cooperate in the quick-make and quick-break operation of the switch a spring 38 is secured at one end to the cross piece 31 and at the 30 other to the insulating block 32 as at 39. An auxiliary flat blade spring 38' may be secured underneath the spring 38 to normally press against the cross-piece 31.

The sockets 26, 26' are preferably flared 35 at their top end as at 40 to facilitate the entry thereinto of the male contact members 43, 43' provided in any suitable manner on the iron or other such electrical apparatus adapted to be used in connection with the 40 stand. Thus, the rear of the iron may be provided with a hood 42 extending therefrom within which are secured the male contact members 43, 43' suitably insulated from the hood as at 44. These contact members 45 are of course electrically connected in any suitable manner to the heating element in the iron (not shown).

The operation of the stand and switch mechanism will now be understood. In the 50 normal "off" position shown in Fig. 4, when the iron 12 is not on the stand, the spring 34 is extended with the block 32 in the highest position of its vertical travel. The spring 38 is then above the line of centers 46 from 55 the pivotal axis of the switch blades to the center 40' and thus pulls upwardly on the rear end of the switch blades 30, 30' and thus maintaining them out of contact with the switch clips 17, 17'. When the iron 12 60 is placed on the stand, the hood member 42 fits over the hood portion 23 of the casting 15^a and the male members 43, 43' register in the sockets 26, 26' and push down simultaneously on the push rods 35, 35' 65 thus causing the block 32 to move downward

and compress the spring 34. This releases the pressure of the flat blade spring 38' against the cross piece 31 and causes the coil spring 38 to move down below the line of centers 46 and pull downward on the rear 70 ends of the switch blades forcing the forward ends into contact with the switch clips thus connecting the switch blades to the electric supply and conducting current through said blades through the sockets 26, 26' and 75 43, 43' to the iron. It will be noted that the block 32 will move downward without tilting about the bolt 33 only if equal downward pressure is brought to bear on both of its ends simultaneously by the simultaneous 80 action of the contact members 43, 43' against the contact members 35, 35'. Should one in any manner seek to insert any foreign member into one of the sockets 26, 26', its pressure against the contact members 35, 35' acting only on one end of the block 32 will merely cause it to jam against the other end without operating the spring 34. Or, if two foreign members are inserted, one in each of the sockets 26, 26', with unequal pressure, 85 there would likewise result no compression of the spring 34 such as to force the switch blades into contact with the switch clips in the manner hereinbefore described. The spring 40 provides a very effective quick- 90 make and quick-break mechanism. As will be readily understood, the position of this spring with reference to the line of centers 46, drawn through the pivotal center of the switch blades and the attaching point of the 95 spring is controlling as to whether the switch blades are in or out of contact with the switch clips. Thus, when the spring 40 is above this line of centers 46, an upward turning movement acts upon the switch 100 blades about their pivotal axis to snap into contact with the switch clips and vice versa. When the spring is below this line of centers 46, a downward turning movement acts 105 upon the switch blades about their pivotal axis to snap out of contact with the switch clips. It will also be noted that the displacement of the spring relative to this line of centers necessary to thus operate the switch blades is very minute and small in 110 comparison with the travel upward or downward of the members 35, 35' to bring about the corresponding displacement of the spring. In consequence, when the iron is placed on the stand, the members 35, 35' are 115 not alive before the members 43, 43' contact therewith and vice versa, when the iron is removed from the stand, the members 35, 35' are dead before the members 43, 43' move out of contact therewith. Thus, any arcing 120 at the contacts between the male contact on the iron 43 and the stand terminals or contact members 35, 35' is eliminated.

It will thus be seen that there is provided apparatus in which the several objects of 125

this invention are achieved and which is well adapted to meet the most severe conditions of practical use.

As various possible embodiments might be made of the above invention and as various changes might be made in the embodiment above set forth, it is to be understood that all matter herein set forth or shown in the accompanying drawings is to be interpreted 10 as illustrative and not in a limiting sense.

Having thus described our invention, we claim as new and desire to secure by Letters Patent:

1. In an electric heating stand for electric irons and the like apparatus, an automatic switch for connecting the electric supply to the iron comprising a pair of contact members connected to the electric supply, a pair of switch members, actuating means for said 15 switch members adapted to electrically connect the same to said contact members, and means for preventing the operation of one of said switch members independently of the other.
2. In an electric heating stand for electric irons and the like apparatus, an automatic switch for connecting the electric supply to the iron comprising a pair of contact members connected to the electric supply, a pair 20 of switch members, actuating means for said switch members adapted to electrically connect the same to said contact member, and means for preventing the operation of one of said switch members independently of the other.
3. In combination with an electric sad iron or the like, having contact members thereon, a stand for said iron comprising a support, means for connecting the electric supply to the iron, comprising an automatic 25 switch mechanism, and movable members in actuating and resilient connection with said switch mechanism, said movable members

being adapted to be operated by said contacts on the iron when placed upon the stand to actuate said switch mechanism.

4. In combination with an electric sad iron or the like apparatus having contact members thereon, an electric heating stand for said iron comprising a support, an automatic switch mechanism for connecting the 50 electric supply to the iron comprising a casing, means within said casing for connecting said stand to the electrical supply and means adapted to be operated by contact members on the iron for connecting the latter to the 55 supply when the iron is placed on the stand, said means comprising socket members adapted to receive said contact members on the iron and members movable within said sockets and in actuating connection with 60 said switch mechanism and adapted to be 65 operated by said contacts on the iron to actuate said switch mechanism.

5. In combination with an electric sad iron or the like apparatus having contact 70 members thereon, an electric heating stand comprising a support for the sad iron, an automatic switch for connecting the electric supply to the iron comprising a pair of contact members connected to the electric supply, a pair 75 of switch members, actuating means for said switch members adapted to electrically connect the same to said contact members, and means for preventing the operation of one of said switch members independently of the other, said means comprising an equalizer member pivoted to said 80 actuating means and adapted to operate to connect the switch blades to the contact members when depressed by said actuating 85 means, said actuating means comprising movable members adapted to be operated by said contact members on the iron.

Signed at New York city, in the county of New York and State of New York, this 90 27th day of March, A. D. 1920.

ART J. SHIRK.
